UNITED STATES PATENT OFFICE

KARL SCHNEEGLUTH, OF AMBERG, GERMANY, ASSIGNOR TO AMBERGER FLASCHENHUT-
TEN A. G., OF AMBERG, GERMANY

GLASS-FORMING MACHINE

Application filed February 24, 1931, Serial No. 517,892, and in Germany December 1, 1930.

My invention relates to glass-forming machines, and more particularly to the blank molds of such machines.

It is an object of my invention to form 5 depressions in the neck of the bottle while the blank is in the blank mold. The depressions are intended to serve as bearings for the ends of the toggle-lever member which is usually provided in bottle-closures.

10 To the end of forming such depressions I provide a pair of oppositely arranged punches which are mounted to be displaced with respect to the blank, and means controlled by the opening and closing of the 15 blank mold for advancing and retracting the punches.

A blank mold will be shown and described which is adapted to be used on an automatic glass-forming machine of the O'Neill type 20 but I am not limited to the adaptation of my invention to this particular machine. In a machine of the type referred to, as described in U. S. Patent 1,315,983, the blank molds are mounted in vertical position on a horizontal 25 carrier which is rotatable about a column. The blank molds themselves are of two-part construction, with their sections hinged to one another and to the horizontal carrier. Cooperating with the lower end of each blank 30 mold is a sectional neck or "finish" mold, and to this finish mold my novel means is applied.

In a preferred embodiment of my invention I provide a sectional punch support 35 which is adapted to be placed on the finish mold and in this support I mount slideable punches in diametrically opposite positions. The punches are controlled by camming faces on the blank-mold sections, and connected to 40 levers which are mounted to rock in the support under the action of pull-back springs. When the blank mold is closed the levers are moved inwardly while their springs are compressed and advance the punches so that they 45 will penetrate into the cavity for the neck of the bottle. When the blank mold is opened the punches are retracted by the springs.

In the drawings affixed to this specification and forming part thereof a blank-mold section 50 and the two punches with their acces-

sories embodying my invention are illustrated diagrammatically by way of example.

In the drawings

Fig. 1 is an elevation of the blank-mold section, one section of the finish mold and 55 one section of the plunger support,

Fig. 2 is an elevation showing one of the support sections, with its plunger bearing in section along its axis, and

Fig. 3 is a section on the line III—III in 60 Fig. 1.

Referring now to the drawings, *a* is a section of the blank mold, the carrier, the other section, and the means for hinging the sections together and to the carrier, having been 65 omitted.

b is one of the finish-mold sections, and *d* is one of the support sections, the mating sections *b'* and *d'*, respectively, being shown in Fig. 3. *g* is the cavity for the reception of the bottle neck in the finish mold. *c* is a circular recess in the front faces of the support sections *d*, *d'* for the reception of the usual 70 plunger and ring. These parts have not been shown as they form no part of the present invention.

f and *f'* are semi-circular grooves in the jointing faces of the sections *b* and *d*, and *r* and *t* are corresponding semi-circular grooves in the mating sections *b'* and 75 *d'*, respectively. It will be understood that the grooves when the sections are assembled, 80 make up cylindrical bores at the joint. *z* and *z'* are bearing blocks projecting from the jointing faces of the support sections *d* and *d'* into circular recesses *e* and *e'* in the outer 85 perimeter of the respective sections. Each block has a bore *t'* and *r'*, respectively, the bores forming axial extensions of the grooves *t*, *f* and *r*, *f'*, respectively.

Mounted to slide in the guide ways constituted by the bores and grooves are plungers 90 *h* and *s*, with pointed ends *k* and *v*, respectively, the ends being shaped in conformity with the desired shape of the depressions in the bottle neck. The plungers have tapped bores at their ends for the reception of threaded pins *l* with heads *o*. Mounted to rock about pins *p* and *w* in recesses *e* and *e'* of the respective sections *d* and *d'* are punch-operating levers *n* and *x*. Each lever at its free end 95 is equipped with a boss *n'* which is slotted at

- m* for the reception of one of the threaded pins *l*, the bosses *n'* engaging washers or flanges on the heads *o*, as best seen in Fig. 2, and projecting from the recesses *e* and *e'*. Furthermore each lever is equipped with a spring *q* in a suitable cavity which is abutted on the corresponding support section and tends to retract the corresponding punch *h* or *s*.
- 10 The lower ends of the sections of the blank mold are equipped with camming faces for the operation of the levers *n* and *x*, as shown at *u* for the section *a*. The cam faces are recessed at *y* for the reception of the bosses *n'* of the respective levers *n* and *x*.
- 15 In operation the section of the finish mold and the support are assembled on the plunger and its ring, not shown, in the position illustrated in Fig. 2, and the blank mold is closed about them. During the closing of the blank mold the camming faces *u* engage the bosses *n'* of the levers *n* and *x* and advance the punches *h* and *s* into the cavity *g* of the finish-mold sections *b*. A quota of glass is
- 20 now placed into the blank mold, separated from the punty rod and finished, as described in the said patent, until the blank is ready to be transferred to a blow mold. When the blank mold is opened the camming faces *u* release the bosses *n'*, and the springs *q*, through the medium of the levers *n* and *x*, retract the punches *h* and *s* from the cavities they have formed in the neck of the bottle.
- 25 I wish it to be understood that I do not desire to be limited to the exact details of construction shown and described for obvious modifications will occur to a person skilled in the art.
- 30 In the claims affixed to this specification no selection of any particular modification of the invention is intended to the exclusion of other modifications thereof and the right to subsequently make claim to any modification not covered by these claims is expressly
- 35 reserved.
- 40 I claim:—
1. In a sectional blank mold a support adapted to be secured in a fixed position with respect to the sections of said mold, a pair of punches arranged in diametrically opposite positions with respect to the axis of said blank mold and mounted to slide on said support, an operating lever connected to each punch, means on the sections of said mold for moving said levers inwardly, and a spring connected to each lever for moving said levers outwardly with respect to said blank mold.
- 45 2. In a sectional blank mold a sectional finish mold adapted to be secured in a fixed position with respect to said blank mold, a sectional support adapted to be placed on said finish mold, the sections of said finish mold and said support together making up guideways in diametrically opposite positions with respect to the axis of said blank mold,
- 50 punches mounted to slide in said guideways, and means controlled by the opening and closing of said blank mold for advancing and retracting said punches.
- 55 3. In a sectional blank mold a sectional finish mold adapted to be secured in a fixed position with respect to said blank mold, a sectional support adapted to be placed on said finish mold and said support together making up guideways in diametrically opposite positions with respect to the axis of said blank mold, a bearing block projecting from the jointing face of each support section into a recess of the mating section and having a bore in continuation of the corresponding guideways in said finish mold and said support, punches mounted to slide in said guideways and in the bores of said bearing blocks, and means controlled by the opening and closing of said blank mold for advancing and retracting said punches.
- 60 In testimony whereof I affix my signature.
- KARL SCHNEEGLUTH.
